UNITED STATES PATENT OFFICE.

AUGUSTE NAMUR, OF NEW YORK, N. Y., ASSIGNOR TO THE TUTTLE & BAILEY MANUFACTURING COMPANY, OF SAME PLACE.

DESIGN FOR A SCREEN FOR A HEATER.

SPECIFICATION forming part of Design No. 15,274, dated August 19, 1884.

Application filed May 12, 1884. Term of patent 14 years.

To all whom it may concern:

Be it known that I, AUGUSTE NAMUR, a citizen of Luxemburg, Germany, residing at New York city, in the county and State of New York, have invented and produced a new and original Design for an Ornamental Screen for Covering Coils of Steam-Pipe, of which the following is a specification.

The accompanying photograph represents a panel of my newly-designed screen for steam-heaters in front elevation.

The essential feature of my design for open fret-work screens consists of a wheel center figure composed of a central ring, *a*, having radial front bars, *b*, joining a fluted ring, *c*, which is joined to the main outer rim, *d*, by radial spokes *e*, said wheel being set in a plain field of cross-bars, *f*, in imitation of woven net-work, and having a parting of the rim at one side, with the ends of the rim connected to bars *g*, extending along the net-work field a short distance parallel to each other, and connecting with the ends of the rim of another wheel in all respects like the first, said bars *g* having a rosette, *h*, in the middle, surrounded by a plain border-frame, *i*. The spokes *e* at the parting of the two wheels are joined together by the parallel bars *j*, and said bars connect with a cross-bar, *l*, extending from one to the other of the border-frames of the rosettes. The field of cross-bars *f* is surrounded by a border-frame consisting of parallel side bars, *m*, and parallel end or top and bottom bars, *n*, said side bars, *m*, being creased or grooved and indented on the surface, and connected together at intervals by parallel bars *o*, having a rosette, *p*, in the middle, and the end border-bars are connected by cross-bars *q*, located at intervals along them, with figures *r* between them resembling, in some respects, the form of a bird with outstretched wings. The corner spaces of the border-frame have fan-shaped figures *t*, arranged in the angles, and below the border-frame is a base-panel of rings, *v*, joined to links *w*, which are joined to the border-frame bar *n* at one end, also to the base-bar *x* at the other end, and also to the inside bars, *y*, of the panel, between which and the outer side bars, *y*, of said panel are other rings, *z*, joined

at the sides to said panel-bars, also joined at the top and bottom to the bars *n* and *x*, respectively, and also joined together by bar *z*. Over the upper end of the border-frame is a top finish consisting of a cross-bar, *a'*, on the ends of extensions of the side border-frame bars, and having intermediate bars, *b'*, extending down to the top border-bar, *n*, with pendant points *c'* intermediate to them, and connected to a wave-bar, *d'*, which crosses the bars *b'* and inside border-frame bars, and terminates in connection with the outside border-bars. As thus far described, the panel is complete for use intermediately to other panels on each side of it; but when employed for an end panel of the screen, I add a corner-finish consisting of a narrow panel of side bars, *m'*, cross-bars *n'*, and top *a'*, inclosing a plate, *b'*, having a vertical row of circular openings, *c'*, at the bottom, an inverted-Y-shaped figure, *d'*, in the space between the lower cross-bars, *n'*, and the side bars, a herring-bone web, *e'*, between the side bars, *m'*, along the middle section of the panel and the radial point figure *f'* in the top space.

I claim—

1. The design for a heater-screen herein shown and described, consisting of the wheel-figures, field of cross-bars, and border-frame, base-panel, and top, as set forth.

2. The design for a heater-screen herein shown and described, consisting of the corner of side bars, *m'*, cross-bars *n'*, and top *a'*, inclosing a plate, *b'*, having a vertical row of circular openings, *c'*, at the bottom, the inverted-Y-shaped figure *d'* in the space between the lower cross-bars, *n'*, and the side bars, a herring-bone web, *e'*, between the side bars, *m'*, along the middle section of the panel, and the radial point figure *f'* in the top space, as set forth.

In witness whereof I have hereunto signed my name in the presence of two subscribing witnesses.

AUGUSTE NAMUR.
